UNITED STATES PATENT OFFICE.

JOHN E. MILLER, OF PITTSBURG, PENNSYLVANIA, ASSIGNOR TO GEGRGE DUNCAN & SONS, OF SAME PLACE.

DESIGN FOR A VESSEL OR DISH.

SPECIFICATION forming part of Design No. 16,594, dated March 30, 1886.

Application filed February 5, 1886. Serial No. 100,939. Term of patent 7 years.

To all whom it may concern:

Be it known that I, JOHN E. MILLER, of Pittsburgh, in the county of Allegheny and State of Pennsylvania, have invented a new and useful Design for Glassware; and I do hereby declare the following to be a full, clear, and exact description thereof, reference being had to the accompanying drawings, forming a part of this specification, in which—

Figure 1 is a side view of a vessel or dish illustrating the design. Fig. 2 is a horizontal cross-section of a part of the circumference of the vessel on the line $x-x$ of Fig. 1.

The dish is ornamented with a series of adjacent waved lines or ridges, which are triangular or prismatic in cross-section. These ridges are escalloped or serrated, as shown in Fig. 1. The upper edge or rim of the vessel is also escalloped, as shown in the same figure.

The leading or characteristic features of my design are indicated in the following claims.

I claim—

1. The design for vessels herein shown and described, the same consisting in a vessel whose sides are provided with a series of escalloped or serrated waved ridges, as set forth.

2. The design for vessels herein shown and described, the same consisting in a vessel provided with a series of waved prismatic ridges, as set forth.

In testimony whereof I have hereunto set my hand this 4th day of February, A. D. 1886.

JOHN E. MILLER.
